UNITED STATES PATENT OFFICE

2,500,133

ENGINE STARTER DRIVE

Donald L. Miller, Elmira, N. Y., assignor to Bendix Aviation Corporation, a corporation of Delaware

Application September 3, 1948, Serial No. 47,638

2 Claims. (Cl. 74—7)

1

The present invention relates to an engine starter drive, and more particularly to starter gearing of the type which automatically connects the starting motor to an engine gear when the starting motor is energized, and disconnects the starting motor when the engine starts.

It is an object of the present invention to provide a novel engine starter drive which is efficient and reliable in operation, simple in construction, and economical to manufacture.

It is another object to provide such a device which incorporates a small number of parts, and is easily assembled.

It is another object to provide such a device in which the parts when assembled, are not subject to displacement or loss of adjustment in use.

The present invention is an improvement on the structure shown in Fig. 4 of applicant's prior application, Serial No. 756,464 filed June 23, 1947, now Patent No. 2,481,324, and concerns especially the stop means which defines the operative position of the drive pinion.

Further objects and advantages will be apparent from the following description taken in connection with the accompanying drawing in which:

Fig. 1 is a side elevation partly broken away and in section of a preferred embodiment of the invention;

Fig. 2 is a similar view showing the parts in cranking position; and

Fig. 3 is a detail in perspective of the screw shaft with the integral stop means for the nut formed thereon.

In Fig. 1 of the drawing there is illustrated a power shaft 1 on which a screw shaft 2 is fixedly mounted as by means of a cross pin 3 retained by a lock ring 4.

A pinion 5 is slidably journalled on the power shaft 1 for movement into and out of mesh with an engine gear 6. Means for traversing and rotating the pinion from the screw shaft is provided comprising a nut member 8 threaded on the screw shaft 2 and having a splined connection as indicated at 9 with one end of a barrel 11. The opposite end of the barrel 11 is rigidly connected as indicated at 12 to a driving overload release clutch member 13 which is journalled on an extension 14 of the pinion against a washer 15 which abuts a shoulder 16 formed by reducing or turning down the teeth of the pinion.

A driven slip clutch member 17 is splined on the hub 14 of the pinion 5 as indicated at 18, and is pressed against the driving clutch member 13 by yielding means here shown in the form of an

elastic washer 19 which is retained on the end of the pinion hub by means of a lock ring 21.

Means normally holding the pinion 5 and barrel 11 in extended relation with respect to the nut 8 is provided in the form of a compression spring 22 within the barrel bearing at one end against the nut 8 and at its other end against a thrust washer 23 which is fixed in the barrel by a lock ring 24. The nut 8 is retained within the barrel by a split thrust ring 25.

Means normally maintaining the parts in idle position are provided in the form of an anti-drift spring 26 bearing at one end against the nut 8 and at its other end against a thrust ring 27 seated on the end of the screw shaft 2.

As best shown in Fig. 3, the screw shaft 2 is formed with a radial flange to limit the travel of the nut 8 toward meshing position. The threads of the screw shaft are milled right through the flange so as to leave radial lugs 28, 29 and 31 which arrest the movement of the nut 8 when the pinion is in meshed position, a thrust washer 32 being preferably interposed therebetween. The lugs 28, 29 and 31 are turned down for a short distance to provide shoulders 33, 34 and 35 against which the thrust ring 27 seats.

The driving overload release clutch member 13 is provided with inclined torque transmitting teeth 36, and the driven clutch member 17 is provided with corresponding teeth 37 which are pressed together by the spring washer 19 so as to transmit torque from the barrel to the pinion. When a predetermined load is exceeded, the teeth 36, 37 wedge themselves apart against the action of the spring washer 19 and slip off the overload until normal conditions are established.

In operation, starting with the parts as illustrated in Fig. 1, rotation of the power shaft 1 and screw shaft 2 causes traversal of the nut 8 with its associated parts to cause the pinion 5 to mesh with the engine gear 6. The longitudinal travel of the nut 8 is limited by abutment of the nut against the thrust washer 32 which accordingly defines the meshing position of the pinion by its abutment against the radial lugs 28, 29, 31 of the screw shaft. The clutch 13, 17 is preferably so loaded by the spring washer 19 that the initial shock caused by engagement of the pinion with the engine gear is cushioned by slippage of the clutch. After cranking has started, it ordinarily proceeds without slippage of the clutch unless a backfire of the engine should cause resistance to cranking to exceed the predetermined maximum, in which case the clutch will again slip in order to cushion the drive.

If tooth abutment between the pinion 5 and engine gear 6 should occur during the meshing movement of the pinion, spring 22 yields and permits the nut 8 to proceed along the screw shaft 2 until the driving torque builds up sufficiently to index the pinion teeth into proper registry with the tooth spaces of the engine gear, after which spring 22 expands and snaps the pinion into mesh, whereupon cranking proceeds as usual.

When the engine fires, the parts are returned to their idle positions by the acceleration of the pinion, the backward movement of the parts being preferably arrested by a thrust washer 38 interposed between the end of the pinion 5 and the screw shaft 2.

Although but one embodiment of the invention has been shown and described in detail, it will be understood that other embodiments are possible and various changes may be made in the design and arrangement of the parts without departing from the spirit of the invention.

I claim:

1. In an engine starter drive a power shaft, a screw shaft fixed thereon, a pinion slidably journaled on the power shaft for movement into and out of mesh with a gear of an engine to be

started, a control nut threaded on the screw shaft, a driving clutch member swiveled on the pinion, a barrel member non-rotatably connected at its ends to the nut and driving clutch member, a driven clutch member splined on the pinion, yielding means holding the clutch members in engagement, yielding means transmitting longitudinal movement from the nut to the barrel, and means positively confining the nut in the barrel, the threads of said screw shaft having radial shoulders in the same plane transverse to the axis of the drive, forming a stop for the control nut to thereby define the fully meshed position of the pinion.

15 2. An engine starter drive as set forth in claim 1 in which said screw shaft has a radial flange providing said stop shoulders for the control nut.
